UNITED STATES PATENT OFFICE.

FRANK W. MOULTON, OF WASHINGTON, DISTRICT OF COLUMBIA.

DESIGN FOR A CIGAR-STAND AND ASH-RECEIVER.

SPECIFICATION forming part of Design No. 18,240, dated April 3, 1888.

Application filed February 28, 1888. Serial No. 265,508. Term of patent 3½ years.

To all whom it may concern:

Be it known that I, FRANK W. MOULTON, a citizen of the United States, residing at Washington, in the District of Columbia, have invented and produced a new and original Design for Cigar-Stands and Ash-Receiver for Smokers' Use, of which the following is a specification, reference being had to the accompanying drawing, forming part thereof.

10 The figure is a perspective view of my newly-designed stand.

The design embraces as its essential features a central or body portion formed in its upper surface with a concave or saucer-like portion, 15 *a*, and a series of concave or grooved arms, *c*,

extending radially outward from the concave portion *a*. The body portion is supported on a series of legs or feet, *b*, usually three in number and arranged underneath the arms *c*.

Having thus described my invention, what I claim is—

The design for a cigar-stand and ash-receiver herein shown and described, comprising as its essential features the dished central body and the series of grooved arms radiating 25 therefrom.

FRANK W. MOULTON.
